UNITED STATES PATENT OFFICE.

GUSTAF OLSON, OF CHICAGO, ILLINOIS, ASSIGNOR OF ONE-HALF TO WILLARD M. McEWEN, OF CHICAGO, ILLINOIS.

ELECTRIC FAN.

1,295,055.

Specification of Letters Patent.

Patented Feb. 18, 1919.

Application filed October 15, 1917. Serial No. 196,615.

To all whom it may concern:

Be it known that I, GUSTAF OLSON, a citizen of the United States of America, and a resident of Chicago, county of Cook, and 5 State of Illinois, have invented certain new and useful Improvements in Electric Fans, of which the following is a specification.

The main objects of this invention are to provide improved cushioning means for oscillating electric fans adapted to cushion the movement of a fan at the ends of its oscillations; to provide improved means of this kind suitable for fans of the general type shown in the patent of Willard M. 10 15 McEwen, No. 1,214,198, issued January 30, 1917, and especially the particular type of fan shown in my prior Patent No. 1,243,968, granted October 23, 1917, and to provide an improved form of spring adapted to be arranged between the fan mechanism and the base, so as to absorb the shock vibrations that occur during the rapid tilting of such fan mechanism.

An illustrative embodiment of this invention is shown in the accompanying drawings, in which:

Figure 1 is a side elevation of an electric fan of the type shown in my prior patent hereinbefore mentioned having the improved 30 spring arranged thereon.

Fig. 2 is an enlarged fragmentary side elevation of the hinge connection of said fan showing the arrangement of the spring.

Fig. 3 is an enlarged detail of the locking 35 pawl for the control lever of said fan.

In the operation of fans such as those shown in the above mentioned patents considerable vibration and jarring often occurs as the fan approaches the limit of its tilting 40 and is reversed. The extent of this vibration and jarring varies according to the size and weight of the fan mechanism, and is always likely to be augmented if the several parts which coact to produce the tilting 45 movement are not carefully made. The present invention is designed to obviate this vibration and jarring.

The cushioning means is herein shown as applied to a device constructed substantially 50 the same as that illustrated in the aforesaid patents. The blower mechanism, which comprises the usual motor (not shown) journaled in a casing 2 and carrying a fan 3 on the shaft 4 of said motor, is tiltably supported on a shaft or member 5 which is ro-

tatably mounted on a base or support 6. A sleeve or member 7 is also journaled on the support 6, concentrically of the shaft 5, and has formed thereon an outwardly disposed annular flange 8 of wavelike form. 60 The upper face of this flange provides a track 9 on which rollers 10, journaled on the motor casing 2, are adapted to travel for the purpose of causing the blower mechanism 1 to tilt back and forth in a vertical 65 plane during a relative rotation of the sleeve 7 and the member 5.

The relative rotation of the sleeve 7 and the member 5 is effected by a gear rack 11 formed on the periphery of the flange 8 and 70 a pinion 12 meshing therewith. The pinion 12 is carried on a shaft 13 journaled in the motor casing 2, and by suitable gearing connects with the shaft 4 of the motor.

The shaft or member 5 has a pair of arms 75 14 formed thereon which extend upwardly and outwardly over the flange 8. The ends 15 of the arms 14 are doubled back at the sides of the flange, so that the mounting for the blower mechanism overhangs the support 80 6. Lugs 16, depending from and integrally formed on the motor casing 2, are pivotally connected to the arm ends 15 by means of pins 17 so as to support the blower mechanism in position to allow it to be tilted in a 85 vertical plane as hereinbefore explained. The axis of the pins is located substantially half-way between the crowns and depressions of the flange 8, so that the rollers 10 have the same action on the track 9 whether 90 traveling over the crowns or the depressions. A tubular passage 5.1 is formed in the shaft 5 through which conductor wires lead from the motor to a source of electricity.

The cushioning or buffer means comprises 95 a spring 18 which is twisted into a sort of S-shaped form with the ends thereof extending in opposite directions substantially transverse to the central portion of the spring. The ends of this spring are secured 100 one to the under side of the casing 2 at one side of the plane of the pivotal connection of the casing to the shaft 5, and the other end is connected to the outer end 15 of one of the arms 14 formed on the shaft 5. 105

The fan mechanism herein shown employs the same principle of operation as that set forth in the above mentioned patent to Willard M. McEwen, wherein by tilting the blower mechanism up and down in a verti- 110

cal plane, through the relative rotation of the member or sleeve 7 and shaft 5, gyratory forces are brought into action which cause the fan to swing back and forth in a horizontal plane. The gyratory forces cause a reversal of the direction of the horizontal swinging movement whenever the vertical tilting movement is reversed, and the rapidity of change in and the angular extent of the horizontal movement depend upon the rapidity of change in and the angular extent of the vertical movement.

As the fan tilts back and forth in its vertical plane, the spring 18 tends to take up any lost motion or absorb any shocks that occur, especially as the fan mechanism reaches the limit of its tilting movement and reverses. Furthermore the spring tends to assist and make easier the change in the direction of tilting.

Control mechanism for regulating the various movements of the fan comprises a lever or finger 19 pivotally mounted on the base 6 and adapted to be swung into an upright position to permit the upper end thereof to either engage a notch 20 formed in the end 15 of one of the arms 14, or engage a groove 21 formed in the face of the member 7. When the finger 19 is seated in the notch 20 the shaft 5 is secured against rotation which allows the member 7 to be rotated and the fan mechanism tilts up and down in a fixed vertical plane. When the finger 19 is seated in the groove 21 in the member 7, said member is held against rotation and the fan mechanism is rotated about a vertical axis and at the same time tilted up and down.

When the finger 19 is in the position shown in Fig. 1 both the shaft 5 and the member 7 are free to rotate, and the fan mechanism oscillates back and forth as it is tilted up and down. In order to limit the angularity of these oscillations a spring 22 is provided, one end of which is secured to a pawl 23 pivotally mounted on the base 6 adjacent to the finger 19, and the other end of which is adapted to be fastened to an eyelet 24 secured on the end 15 of one of the arms 14. When this spring is fastened in the position shown in Fig. 1 with the upper end attached to eyelet 24, the pawl 23 is elevated to the position shown in Figs. 1 and 3, so that the shoulder 25 on said pawl is disposed so as to prevent the finger 19 from being thrown upwardly into a position to engage either the notch 20 or the groove 21. This avoids the possibility of the finger 19 being set to engage the notch 20 or the groove 21 when the spring 22 is arranged to limit the angular movement of the fan mechanism.

Although but one specific embodiment of

this invention has been herein shown and described, it will be understood that numerous details of the construction shown may be altered or omitted without departing from the spirit of this invention as defined by the following claims.

I claim:

1. In an air circulating device, the combination of a support, a member journaled thereon, arms on said member extending outwardly therefrom and having their ends doubled back at the sides of said support, blower mechanism, lugs on said blower mechanism pivotally connected to said arm ends, coacting means on said support and blower mechanism adapted to tilt said mechanism, and yielding means interposed between said blower mechanism and one of said arms and adapted to cushion the tilting movements of said blower mechanism.

2. In an air circulating device, the combination of a support, a member journaled thereon, arms on said member extending outwardly therefrom and having their ends doubled back at the sides of said support, blower mechanism, lugs on said blower mechanism pivotally connected to said arm ends, coacting means on said support and blower mechanism adapted to tilt said mechanism, and a spring interposed between said blower mechanism and one of said arms and adapted to cushion the tilting movements of said blower mechanism.

3. In an air circulating device, the combination of a support, a member rotatably mounted thereon, blower mechanism tiltably mounted on said member, mechanism for tilting said blower mechanism whereby it will be caused to oscillate in a plane transverse to that in which it is tilted, and a substantially S-shaped spring wire having one end connected to said blower mechanism and the other end to said member and adapted to cushion the tilting movements of said blower mechanism.

4. In an air circulating device, the combination of a support, a member journaled thereon, arms on said member extending outwardly therefrom and having their ends doubled back at the sides of said support, blower mechanism, lugs on said blower mechanism pivotally connected to said arm ends, coacting means on said support and blower mechanism adapted to tilt said mechanism, and a substantially S-shaped spring wire having one end thereof connected to said blower mechanism and the other end connected to one of said arms and adapted to cushion said blower mechanism.

Signed at Chicago this 13th day of October, 1917.

GUSTAF OLSON.
